METHOD OF PUNCHING MULTICOLOR PRINTING PLATES

Otto Seffzig, Berlin, Germany

Application November 2, 1937, Serial No. 172,432
In Germany October 21, 1936

1 Claim. (Cl. 164—125)

For the multi-colored art printing, etched plates or galvanos are usually employed as printing plates, several galvanos of one original etching being necessary according to requirement, in order to satisfy the demands of the book, art and multicolored printing.

The known machines, for instance also the so-called Iris press, can not yet work satisfactorily, as they require curved printing plates, in which the sensitive screen-picture is distorted so that an accurate registering cannot be attained.

In order that the printing plates when printing the one into the other give an accurate fitting, fitting crosses are drawn on the outer edges of the individual printing plates. These fitting crosses serve during the print and trial printing as directing means for the production of the so-called first prints for the control relating to fitters, and they have fulfilled their object as soon as the first print has been declared fit for use. As in most instances, for the reason of editions or of precaution, galvanos are first produced, the fitting crosses remain on the projecting rims of the zinc or copper etchings, although they are no longer needed in the manufacturing proceeding of the galvanoplastic. As the fitting crosses have no value whatsoever for the printer, they are removed prior to the insertion of the printing plates into the machine.

The adjusting of the different colored part-printing plates in the printing press makes not too great difficulties when printing with flat part-printing plates, as displacing of the flat lying printing plates towards all directions, that is also in diagonal direction, is possible and therefore an accurate fit can be attained without difficulty when printing the one into the other. As, however, the output of printing presses working with flat printing plates is less than that of rotary printing presses, it has been proposed to use the rotary printing also for multicolored book printing.

It is then necessary, to employ for the plate-cylinder round printing plates which have to be produced by bending flat printing plates or electrotypes, whereby, however, distortions of the screen-picture occur. The printer, who mounts the printing plate onto the plate cylinder, cannot, as in the flat printing, shift the printing forms towards all directions as shifting in diagonal direction is not possible. Further, the fitting crosses are wiped out more and more during the gradual production of the deposits and, after the rear side has been coated with tin they are no longer visible at all, so that when inserting

the deposits into the round-casting apparatus for back-casting of the deposits the caster is dependent for the adjusting only on his feeling and on his eye. This is, however, as experience has shown not sufficient.

The invention relates to a method for rendering possible the fitting insertion of the individual deposits necessary for a multi-colored printing into a round-casting apparatus for the back-casting of the deposits, the chief characteristic feature of which consists in that the deposits having in known manner fitting crosses are perforated with small holes at the points of intersection of the fitting-cross lines, these holes serving as fixed points during the production of larger holes in the deposits which with the wider holes are hung on accordingly thick pins in the casting apparatus. The deposits are threaded preferably on fitting pins of a perforating device with the holes provided on the fitting crosses; in this perforating device the holes are made in the deposits by means of which holes these deposits are fixed for the back-casting on pins of the casting apparatus, so that separate adjusting is not necessary. The fitting crosses are therefore used as important starting points during the back-casting of the deposits for the production of the round plates. Only after the perforating of the deposits, that is after the larger holes have been made which serve for hanging the deposits into the casting apparatus, the fitting crosses are no longer required.

The small holes in the points of intersection of the fitting crosses on the deposits are produced with a needle-like tool. The perforating device has two adjustable fitting pins, which are adjusted and secured in the adjusted position according to the fitting crosses of any color-deposit. The other copper-deposits threaded on the fitting pins are always in an accurately registering position. By the perforating rams of the perforating device carrying the fitting pins larger holes are made in all deposits which therefore are always in accurately registering position. If the copper deposits are hung into the casting apparatus on pins preferably placed near the casting mouth, all deposits in the casting apparatus are in a fitting position.

The device for carrying out the method according to the invention is illustrated, by way of example, in the accompanying drawing in which

Fig. 1 shows the deposits ready for insertion into the casting machine.

Fig. 2 is a cross-section through the perforating device.

Fig. 3 is a vertical cross-section through a round-casting apparatus, and

Fig. 4 shows a detail of the casting mould on enlarged scale.

5 In the deposits *a* small holes *c* are made in the point of intersection of the lines of the fitting crosses, said holes enabling to thread the deposits or the like onto the pins *d* mounted in a plate *f* of a perforating device *e*. The diameter of these 10 pins correspond accurately to the diameter of the small holes *c*, so that the deposits threaded on the pins *d* are all accurately secured in their position. This is necessary as the larger holes *k* which are made by the perforating rams *h* of the 15 perforating device *e* in the deposits *a* threaded on the pins *d* must have a quite determined, invariable position relative to the holes *c* in the point of intersection of the lines of the fitting crosses *b*. The plate *f* of the perforating device 20 is preferably of the size of the deposits *a*. The pins *d* arranged on plate *f* are preferably adjustable and for instance adapted to be secured in their adjusted position by means of a screw *g*. The perforating device may comprise two or more 25 perforating rams *h* adapted to be moved singly or both at the same time by means of a hand lever *i*. By these perforating rams *h* the holes *k* are stamped into the deposits *a*, the stamping pin *r* determining the hole-diameter. On the casting 30 apparatus *m* means are arranged near the casting mouth *o* which serve for suspending the deposits *a* into the casting apparatus. These means consist preferably of a bolt *s* mounted so that it can be shifted in axial direction and carrying at its front end a pin *n*. The diameter of this pin *n* corresponds accurately to that of the stamping pin *r* or of the holes *k* in the deposits *a*. The bolts *s* have annular grooves *p* serving as 35 notches for a locking bolt *q* and permitting to bring into or out of engagement the pins *n* with

the holes *k* of the deposits inserted into the casting apparatus *m*, the distance between the pins *n* corresponding to that between the holes *k*.

By the method according to the invention a very accurate fitter for the production of the 5 multi-colored printing plates for rotary printing can be attained without difficulty and without the necessity of difficult adjusting of the printing plate to be back-casted in the hot casting apparatus.

10

As, owing to the invention, the fitting crosses are no longer wanted for the insertion of the deposits into the casting apparatus, the corresponding rim of the deposits can be cut off, as soon as the holes *k* have been stamped into the 15 deposits. A clean trimming of the deposits is then no longer necessary. The technical progress obtained by the invention consists therefore chiefly therein that it is now possible to produce the colored-part-printing-plates for rotary printing directly as perfect round plates in the desired 20 radius, whereas it was hitherto necessary, to bend the plane part-color-printing plates whereby a defective picture production had to be taken into account as a great inconvenience owing to the 25 distortion of the screens.

20

I claim:

A method for enabling the fitting insertion of the individual galvanic deposits of colored etchings necessary for a multi-colored printing into 30 round casting apparatus for back casting of the deposits, and in which fitting crossed lines are formed on the deposits, said method consisting of perforating the fitting crossed lines on the deposits at the points of intersection of the crossed lines 35 and using said perforations as stationary points and then producing larger holes in the deposits at other points for hanging up the deposits in the round casting apparatus.
